UNITED STATES PATENT OFFICE.

EMIL O. ECKLAND, OF MENOMINEE FALLS, WISCONSIN, AND WALTER H. YOUNG, OF CHICAGO, ILLINOIS.

FLUID FEEDING AND CONDUCTING MEANS.

Application filed October 9, 1922. Serial No. 593,473.

This invention relates broadly to fluid feeding and conducting means, and more particularly to an improved method of and apparatus for conducting fluid to and for applying and distributing such fluid upon various materials, more especially to the provision of such apparatus for replenishing the inking tape of a typewriting or calculating machine, and for other similar purposes.

While this invention is illustrated, for the sake of convenience, as embodied in apparatus for supplying and applying ink to the inking tape of typewriting and calculating machines, it will be understood that it is not limited to such an adaptation, but finds a wide field of utility for other purposes.

It is well known that for furnishing ink for the type in a typewriting or adding machine the general practice has been to provide a continuously moved ribbon or tape which has been previously saturated with an inking fluid, which latter is pressed from the tape onto the paper when struck by the type. While the ribbon or tape eventually becomes worn and must be replaced, it will often dry out before its fabric has lost its usefulness, and result in the work done by the machine becoming faded in appearance due to loss of ink.

It is one of the primary objects of this invention to provide a simple and inexpensive attachment which may be readily applied to standard typewriting or adding machines for maintaining the inking ribbon or other base always saturated until such ribbon or base has become worn beyond usefulness, and to this end the invention is characterized by the further objects and advantages which reside in the provision of improved means for supplying and applying a fluid to a base for purposes such as that referred to; the provision of an improved method of and means for maintaining the degree of saturation of a type writing machine inking tape or the like constant; the provision of improved means for maintaining a fixed degree of impregnation of a fluid impregnated body; the provision of an improved method of and apparatus for impregnating a body of material with fluid; the provision of an improved method of and apparatus for impregnating or saturating a body with fluid by capillary action; the provision of an improved method of and apparatus for sup-

plying and applying to a moving body a fluid by capillary action; the employment of capillary action to the attainment of new method of feeding fluid; the provision of an improved method of and apparatus for carrying out such method whereby to maintain an impregnated or saturated body against drying; and the introduction of the foregoing features and advantages into an improved structural embodiment capable of installation on various machines, such as either typewriting or calculating machines, for the purpose of maintaining the inking ribbon or tape impregnated to a fixed degree.

It is a further object of this invention to provide an inking device possessing the foregoing characteristics whereby a continuous inking ribbon or tape may be employed on a typewriting or calculating machine, and in like apparatus, thereby eliminating the reversing mechanism which is usually employed for winding the tape first on one and then on the other of the reels provided for this purpose.

The foregoing and such other objects and advantages as may appear or be pointed out hereinafter are attained in one structural embodiment illustrated in the accompanying drawings, in which:

Figure 1 is a top plan view of the device of this invention constructed for use in application to a typewriting machine;

Figure 2 is an enlarged vertical transverse sectional view taken on line 2-2 of Figure 1, looking in the direction indicated by the arrows;

Figure 3 is a vertical sectional view taken on line 3-3 of Figure 2, looking in the direction indicated by the arrows;

Figure 4 is a perspective view of a detail part;

Figure 5 is an elevational view of an alternate form of this device;

Figures 6 and 7 are views of modified forms of this invention;

Figure 8 is a side elevational view of a modified form of this invention especially adapted for installation on a calculating machine;

Figures 9 and 10 are end elevational and top plan views, respectively, of the device of Figure 8;

Figures 11 and 12, are longitudinal and transverse vertical sectional views, respectively, taken on the lines 11-11 and 12-12

of Figures 9 and 8, respectively, looking in the direction indicated by the arrows.

The improved method or process which is carried out in this invention includes the 5 step of conveying and introducing fluid in (where used for the inking tape of a typewriting or similar machine) by a capillary, such as a wick, to a second capillary, which latter is presented to and in contact with 10 a distributing element for applying the ink to the inking tape or other ink carrying base, such base being formed usually of absorbent material, the fluid ink thereby becoming distributed throughout the inking 15 tape and maintaining such tape substantially at the saturation point at all times. The method thus employed requires no regulation, because the law relating to capillary action governs and as long as the source of 20 supply is maintained the capillaries and the tape will be always impregnated to a fixed degree, and thus the inking tape cannot contain too much or too little ink. In other words, saturation will result from capillary 25 action, and no more fluid can rise in the capillary than that sufficient to maintain saturation. The advantages of such a method over a forced or gravity feed, regardless 30 of control of the latter, can be readily appreciated.

As a means for carrying out the method referred to we have provided several structural embodiments, as shown, reference, in detail, being first had to Figures 1 and 4, 35 inclusive.

In Figure 1 the device is illustrated as installed upon a conventional well-known make of typewriting machine, the frame 5 of such machine being fragmentarily shown, 40 from which the bracket 6 extends for supporting one of the inking tape reels 7, upon which is wound the inking tape or ribbon 8. The tape 8 is trained over an idler roller 9, thence through the inking device A of 45 this invention, and vertically displaceable guide 10, in front of the paper roll 11, thence to the other reel, not shown.

The inking device of this invention may be formed as a part of the typewriting machine, but we have here shown it as a unit attachment for the machine, and therefore the article itself preferably comprises a divided clamp 12, provided with a bifurcated portion 13 for engagement with a bolt or 50 screw 14 on the frame 5, said clamp having screws 15—15 for frictionally adjustably engaging a tube 16, which tube is connected at 17 with a container 18 for fluid ink, and at 19 with the inking device A. The tube 16 55 serves for supporting the container and inking device as a unit, and also as a conduit for a capillary, such as a wick 20, which has one end lying in the container 18, the outer portion of said wick being wound about the 60 outside of an upstanding extension 21 of the

tube 16, as best seen at 22 in Figure 3. The container 18 has a removable cap 23 by which the contents of the container may be replenished, it being observed as important that the container 18 is located below the 70 plane of the inking device A, so that fluid will issue from the container only by capillary action, with the wick portion 22 as a point or station of supply.

The inking device includes the base A, 75 affixed, as explained, to the tube 16, said base having a stud bolt 24 engaged therewith and secured by a nut 25, and on said bolt is mounted a revoluble roller 26 preferably of wood or a similar material. On 80 each side of the roller there is provided one each of the vertical fingers 27 and 28, and the tape 8 is trained alternately over said roller and under or back of said fingers as shown in Figure 1. 85

Ink or similar fluid is conveyed by the wick 20, and saturates the portion 22, whence such ink is conveyed to the tape 8, via the roller 26, by the provision of a continuous distributing wick 29. The wick 29, 90 which is nothing more than a fine thread, is carried on a plate 30, which latter is detachably and by its own weight and friction, held on the pins 31 and 32 upstanding from the base A. The plate 30 has a plurality of 95 eyes 33 through which the thread or wick 29 is trained, said wick having a slack portion 34 lying in direct contact with the wooden roller 26 and another slack portion 35 in contact with the portion 22 of the wick 100. A helical spring 36 surrounds the wick 29, said spring being attached at 36^a to the plate 30, and this maintains the wick 29 under tension in contact with the wick portion 22, and roller 26, as well as cooperating 105 with the weight of plate 30 to prevent displacement of the latter.

It will be observed that as the tape 8, in the course of operation of the typewriting machine, is drawn step by step past and over the roller 26 in surface contact therewith, the distributing roller 29 contacting with wick 29, and thereby will collect ink from the wick 29. The ink thus collected is distributed upon the tape 8, so that it is constantly maintained at the saturation point. 110

We have found in actual tests that for ordinary operation a single thread or wick, such as 29, will suffice, but where desired, two or more of such wicks may be grouped as indicated at 30^a and 30^b, Figure 5. In some instances, where the step is desired, the single wick 29 may be canted, as indicated in Figure 7, so that the wick will lie diagonally across the face of the distributing roller 26. This is, however, not essential to the efficient operation of the device and may be accomplished in one of at least two ways, namely, by boring the holes 37 in the plate 115 120 125 130

30 at an angle to the perpendicular, or by lifting the right hand edge of the plate, as viewed in Figure 7, and engaging the wick 29 between two of the higher convolutions 5 of the wick portion 22.

Figure 6 illustrates a bank or group of the ink distributing devices, all of them being canted.

Referring now to the form of this invention shown in Figures 8 to 12, inclusive, this structure is designed particularly as a unit attachment for application to a standard type of calculating machine. A frame F is provided, comprising end standards 10 39-39 in spaced relation, a base plate 40 supported thereby, and end bearing lugs 41-41, all formed preferably of and struck from a single piece of heavy sheet metal. Supporting brackets 42 and 43 are also 20 formed integrally with the base 40.

A container 44 for fluid ink is carried by the frame F on one of the end bearings 41, and a conduit 45 containing a capillary, such as the wick 46, extends from said container 25 up along the inside of the adjacent bearing lug. A wooden roller 47 is revolvably mounted between the lugs 41, on a shaft 48 carried by said lugs, and the inking tape 49 is trained over and above said roller, as 30 seen in Figure 8. The shaft 48 is held against displacement by the nuts 50.

The capillary or wick 46 is wound about the upper transverse rod 51, as indicated at 35 52, which rod is fixedly mounted in the brackets 42. Similarly, a transverse lower rod 53 is fixedly mounted in brackets 43, and may be provided with an absorbent covering 54.

Ink is conveyed from the wick portion 52 40 to the distributing roller 47 by the provision of a distributing capillary such as the absorbent thread or wick 55, which thread or wick has a slack portion 56 in continuous contact with the roller 47, said wick 55 being trained through one or two of the convolutions of two helical springs 57 and 58, secured to the standards 39, thence said wick passes over the wick portions 52 and 54. The bottom portion of the wick 55 lies below 45 the base plate 40 and passes through a helical spring 59 secured at 60 to the underside of said base. If desired, the wick 55 may be divided, and one of each of the ends thereof secured to the ends of said spring 59. In any event the wick 55 is maintained 55 under tension. The fluid ink is taken up by the wick 46 and saturates the portion 52 whence it flows by capillary action to the distributing capillary 55, which latter has two 60 of its portions 56 in direct contact with the roller 47. It will be obvious that the operation of this device is substantially identical with that shown in Figures 1 to 7, inclusive, 65 with principal exception that a greater area of contact is required for the larger tape

usually used in calculating machines. The absorbent covering 54 takes up ink and prevents such fluid from passing into the portion of the wick 55 below the rod, which would otherwise be deposited on the device 70 or some part of the machine.

In both of the forms of the invention as shown the distributing capillary may move, if desired, but such movement is not essential to the successful efficient operation of 75 this invention. It is, however, an essential feature of this invention that the wick portions 22 and 52 form, in effect, ink feeding stations from which the fluid ink is taken in a sense automatically. The wooden roller, 80 as shown, being but slightly absorbent will not take up too much ink, and when the machine is not in use the roller prevents the accumulation of any great quantity of ink, which would drop into the mechanism of 85 the machine. This, furthermore, lends to the cleanliness of the device.

While certain specified structural features have been set forth, it will of course, be understood that minor alterations to suit 90 various installations may be made without departing from the spirit and scope of the claims.

We claim:

1. The combination with a typewriting 95 machine, having an inking tape, of a reservoir containing ink, a distributing member in contact with said tape, a supply capillary conductor extending into said reservoir, and a distributing capillary conductor in contact with said supply capillary and with said distributing member at a plurality of points. 100

2. The combination with a typewriting machine having an inking tape, of a reservoir containing ink, a distributing member 105 in contact with said tape, a supply capillary conductor, extending into said reservoir, and a distributing capillary conductor of relatively limited area, in contact with said supply capillary and with said distributing 110 member at a plurality of points.

3. The combination with a printing machine having an inking tape, a container, a capillary member for drawing fluid ink from said container, a distributing member, and an endless auxiliary capillary member in contact with said first mentioned capillary member and said distributing member. 115

4. The combination with a printing machine having an inking tape, a container, a capillary member for drawing fluid ink from said container, a distributing member, and an endless auxiliary capillary member in contact with said distributing member at a plurality of places and in contact with said 120 first mentioned capillary member. 125

5. The combination with a printing machine having an inking tape, a container, a capillary member for drawing fluid ink from said container, a distributing member, 130

- and an endless auxiliary capillary member in contact with said first mentioned capillary member and said distributing member and means for placing said auxiliary capillary member under constant tension. 5
6. The combination with a printing machine having an inking tape, a container, a capillary member for drawing fluid ink from said container, a distributing member, 10 and an endless auxiliary capillary member in contact with said first mentioned capillary member and said distributing member and yieldingly resistant means for placing said auxiliary capillary member under constant tension. 15
7. In a device of the character described, in combination, an absorbent fluid carrying element, a source of fluid, capillary means in communication with said source, an auxiliary capillary means for distributing such fluid, means for placing said auxiliary capillary means under tension, and means receiving such distributed fluid for applying the fluid to said absorbent element. 20
8. In a device of the character described, in combination, a movable absorbent fluid carrying element, a source of fluid, capillary means in communication with said source, an auxiliary capillary means for distributing such fluid, at a plurality of separated points, and means receiving such distributed fluid for applying the fluid to said absorbent element at a plurality of points. 25
9. In a device of the character described, in combination, a movable absorbent fluid carrying element, a source of fluid, capillary means in communication with said source, an auxiliary capillary means for distributing said fluid, at a plurality of separated points, 30 and revoluble means receiving such distributed fluid for applying the fluid to said absorbent element at a plurality of points. 40
10. In a device of the character described, in combination, an endless absorbent fluid carrying element, a source of fluid, capillary means in communication with said source, a second capillary means for distributing such fluid, and means receiving such distributed fluid for applying the fluid to said absorbent element. 45
11. In combination with a typewriting machine having a movable absorbent fluid carrying element, of a roller in contact with said element, a source of fluid supply and a pair of wicks, one of said wicks leading to said source of supply and the other in contact with said roller for distributing fluid thereon and means for placing said last named wick under tension in firm contact with said roller. 55
12. In a typewriter having a ribbon movable longitudinally and transversely, in combination with a movable capillary to be continuously saturated with a writing fluid, of a roller in contact with said element, and means for delivering fluid to said roller at a plurality of separated points, all of said points of delivery being within the area defined by the width of said ribbon absorbent element. 60
13. In a device of the character described, in combination with a movable absorbent fluid carrying element, of a roller in contact with said element, a source of fluid supply, and a pair of wicks, one of said wicks leading to the source of supply and the other of said wicks being in contact with said roller for distributing fluid thereon, and means for maintaining one of said wicks under tension. 65
14. In a device of the character described, in combination with a movable absorbent fluid carrying element, of a roller in contact with said element, a source of fluid supply, and a pair of wicks, one of which wicks is in contact with said roller for distributing fluid thereon, and the other of said wicks associated with said fluid supply, and means for maintaining said distributing wick under tension against said roller. 70
15. The combination with a movable absorbent element, of a reservoir for fluid, a roller and an endless fluid conductor receiving fluid from said reservoir and for delivering such fluid on said roller for application to said absorbent element. 75
- In testimony whereof we affix our signatures at 36 W. Randolph Street, Chicago, Illinois.
